DUMPING CONVEYER MECHANISM FOR FURNACES

Application filed December 8, 1927. Serial No. 238,731.

This invention relates to improvements in conveyer mechanism suitable for use in connection with heat treating furnaces where the articles to be treated are required to be placed 5 in pans or containers and the container contents dumped before the containers pass out of the furnace.

The invention has for its object to provide a simple and reliable means for dumping 10 the container contents. In accordance with this invention there is provided within the furnace a track, the continuity of which is interrupted by an unbridged space which forms the mouth of a chute into which the 15 articles contained in relatively shallow containers are to be dumped before the containers are allowed to pass out of the furnace. The containers are entered into the furnace by being placed on a loading platform or track 20 extension in front of the furnace and are pushed into the furnace by a reciprocating pusher. The containers upon arriving immediately in front of the chute are taken in tow by another forwarding mechanism which 25 moves them across the mouth of the chute in a manner to allow the containers to tilt on a transverse axis whereby to dump the container contents. This additional forwarding mechanism is a reciprocating mechanism having a stroke which is considerably longer than 30 the distance across the mouth of the chute. This forwarding mechanism in addition to moving the containers across the point of dumping also serves to move the containers 35 out of the furnace after the containers have been dumped. For a further understanding of the invention reference is made to the detailed description taken in connection with the accompanying drawings forming part of 40 this specification.

Referring to the drawings, Fig. 1 is a plan view of a portion of the improved conveyer and dumping mechanism, the view being taken inwardly of the longitudinal center line 45 of the mechanism. In this view one of the containers is shown in dumping position and part way across the unbridged space or chute mouth.

Fig. 2 is a side elevation of the conveyer and 50 dumping mechanism parts being in section,

the mechanism being shown in combination with a heat-treating furnace which has been more or less diagrammatically illustrated.

Fig. 3 is an end elevation showing how the containers are supported on the tracks. 55

Fig. 4 is a transverse section through one of the containers.

In the drawings, 10 generally indicates a straight-away track, the continuity of which is interrupted as at C by the mouth of a chute generally indicated in Fig. 2 at 12. For convenience of description that section of track leading toward the chute is identified by reference character "a" and the other section of the track leading away from the chute by "b". 60 The track preferably consists of side rails 10^a and a central rail 10'. Shallow pans or containers 14 are adapted to be moved over the tracks toward and away from the mouth C of the chute. In order to prevent the containers from jumping off the tracks, the latter are provided with upstanding flanges and the bottom of the containers are provided with depending ribs or webs 16 for riding on the 65 tracks. 70

Referring to Fig. 2, letter F indicates any suitable heat treating furnace through which the containers may be passed, it being noted that the mouth of the chute 12 is within the furnace adjacent to the discharge end thereof. The track section "a" will extend beyond the entrance end of the furnace and constitute a loading platform for the containers. The containers are periodically advanced toward the chute a given distance by a transversely 80 extending pusher bar 18 adapted to be reciprocated by any suitable mechanism, a part of which is indicated at 19, said distance being 85 equal to the width of a container.

The mechanism for carrying the containers across the space C will now be explained. Bridging the space C at each of the two sides thereof is a channelled way 20. The bottom of this way near the front of the chute dips downwardly as indicated at 22 and continues forwardly some little distance as indicated at 24. It may then be continued upwardly for a short distance as a wall 26. 28 indicates a bar for which the way 20 forms a support. To one end of this bar is pivotally connected 90 95 100

on a transverse axis a hook-like member 30. In Fig. 2 the hook is shown as resting within the pocket formed by the depressed bottom 24 of the way. This bar 28 extends through the exit end of the furnace for a suitable distance. The underside of the bar is provided with a rack 32 for an appropriate part of its length for meshing with a pinion 34 secured on a shaft 36. This shaft is connected by a suitable train of gears 37 to a motor 38 of the reversible type. When the motor is energized it will rotate in one direction for a given number of revolutions to move the bar 28 a predetermined distance in one direction and then reverse and move the bar back the same distance. Reversing motors of this type are well known in the art and need not be further described. Any other suitable mechanism for reciprocating the bar may be employed. It may be stated at this point that the bar 28 is reciprocated in synchronism with the pusher bar 18 in such a manner that when the pusher has reached the limit of its inward stroke the bar 28 will begin moving in the same direction to take up the progression of the container nearest the chute. The mechanism for initiating the operation of the motor 38 for the described purpose may be of any suitable form, as for example, a switch mechanism 40 arranged in a circuit 42 of the motor, this switch mechanism being actuated by the pusher 18 through a suitable element 44 secured to the pusher 18 as conventionally illustrated in the drawings.

Each container 14 is provided with aligned trunnions 46 of a length to extend over the ways 20. These trunnions are arranged forwardly of the transverse center line of the containers 14 in order that when the containers are supported by the trunnions they may tilt to dump the contents of the containers. Ordinarily the trunnions 46 will be positioned at the extreme forward end of the containers as shown in the drawing. When the hook 30 is in the position shown in Fig. 2, which position may be called its normal position, the tip of the hook is below the trunnion 46 and consequently the containers may be pushed along without interference between the trunnions 46 and the hook 30. The hook 30 being pivotally attached to the bar 28 will of course ride up the incline 22 and onto the way 20 when its bar 28 moves forwardly and will carry the container along with it by engaging with the trunnions. As the hooks are drawn along the way 20, the container will of course begin to tilt as soon as the end of the container most remote from the trunnions 46 leaves the track section "a".

The free end of the container upon leaving the track section "a" will move down the sloping side 50 of the chute, and will eventually swing free whereupon the container will assume a substantially perpendicular position as shown in Figs. 1 and 2. The side wall of

the chute nearest the exit end of the furnace has a curved or cam-like surface as indicated at 52. The pendant container will eventually abut said curved part 52 and be again tilted on its trunnions until it reaches a horizontal position on a level with the track section "b" on which it continues its further progress. The hook 30 pulls the container far enough along to bring it outside of the furnace a distance preferably somewhat greater than the width of the container. The containers after having arrived on the track section "b" are moved therealong step by step as the hook mechanism reciprocates as will now be readily understood. In other words, when the hook disposes a container on the track section "b" the container will engage with the container last disposed on the track and move it along. In so far as this particular invention is concerned the containers 14 after having arrived on the track section "b" outside of the furnace may be removed therefrom in any suitable manner and again positioned on the track section "a" leading into the furnace, it being understood that the materials to be heat treated are placed within the containers at some appropriate point.

As the trunnion end of the container leaves the track section "a" it will tip downward as shown in Fig. 2 until the trunnions 46 rest on the top of the channelled way 20. The trunnions are now in position to be engaged by the hooks 30 as they move forward as will be readily understood from the preceding description.

In view of the fact that a separate mechanism is employed for continuing the progress of the containers after they have arrived at the chute ready for dumping their contents, it will be readily appreciated that no interference between the containers can occur during the dumping period of their movement.

The conveyer mechanism of the present invention is simple and practical and provides for variation in dimensions of the containers from a cold to a hot state. It is quite immaterial to the dumping mechanism where the container approaching the chute happens to stop on the forward limit of the pusher bar so long as it stops some place forwardly of the normal position of the hook. In other words, the range of stopping position of the container is about equal to the width of the container. This lee-way is amply sufficient to take care of any minor differences in width of the containers and of expansion of the series of containers between the pusher bar 18 and the normal position of the hook 30 in front of the chute.

Although we have shown an operative device, still it will be obvious that any changes may be made in size, shape or arrangement of parts without departing materially from the spirit of the invention and we wish there-

fore that our showing be taken in a sense diagrammatic.

What is claimed is:

1. A conveyer comprising in combination, a track having its continuity interrupted by an unbridged space, containers adapted to be moved along the track, means reciprocable alongside said space, and means for establishing pivotal connection between the containers and said reciprocable means to move the containers across said space whereby the containers may tilt about the connection to dump the container contents into said space in moving thereacross.
2. A conveyer comprising in combination, a track having its continuity interrupted by an unbridged space, containers adapted to be moved along the track, means reciprocable alongside said space in parallelism with said track, trunnions on the containers overlying the reciprocable means, and means movable with the reciprocable means for establishing rocking connection with said trunnions to move the containers across said space, whereby the containers may turn on their trunnions to dump the container contents.
3. A conveyer comprising in combination, a track having its continuity interrupted by an unbridged space, containers adapted to be moved along the track, means reciprocable alongside said space in parallelism with said track, trunnions on the containers overlying the reciprocable means, and articulated means for establishing connection between the reciprocable means and the trunnions to move the containers across said space.
4. A conveyer comprising in combination, a track having its continuity interrupted by an unbridged space, containers adapted to be moved along the track, means reciprocable alongside said space in parallelism with said track, trunnions on the containers overlying the reciprocable means, and vertically movable means for establishing connections between the reciprocal means and the trunnion to move the containers across said space.
5. A conveyer comprising in combination, a track having its continuity interrupted by an unbridged space, containers adapted to be moved along the track, means reciprocable alongside said space in parallelism with said track, trunnions on the containers overlying the reciprocable means, prone-lying hooks pivoted to the reciprocable means, and means for elevating the hooks into operative engagement with the trunnions to move the containers across said space while hanging from their trunnions.
6. A conveyer comprising in combination, a track having an unbridged space, containers movable on the track, trunnions projecting from the containers laterally of the track, an upturned hook normally occupying a position in advance of said space below the level of said trunnions, a hook-supporting way at a

level above said normal position whereby the hook when resting on the way will assume a position to engage with the trunnions, means for elevating the hook onto said way, and means for moving the hook forwardly a sufficient distance to carry the containers beyond said space whereby the containers after being carried across the said space may be deposited on the continuation of said track.

7. A conveyer comprising in combination, a track having an unbridged space, containers for movement across the track, a pair of trunnions on each container one at each side, a bar reciprocable in parallelism with the track one at each side of said space, an upturned hook pivotally secured to the free end of each bar the hook normally occupying a position in advance of said space and below the level of said trunnions, a hook-supporting way at a level above said normal position of the hook whereby the hook when resting on the way will assume a position to engage with the trunnions, an arcuate surface up which the hook rides onto said way as its bar moves in the direction of travel of said containers, means for pushing the containers step-by-step toward said space a distance substantially equal to the width of a container, means actuated by the pusher means to start one complete reciprocation of said reciprocable bar, the containers being adapted to turn about their trunnions in moving across said space whereby to dump the container contents, and an arcuate surface up which the tilted containers may ride onto the continuation of said track, the hooks being moved by the bars beyond said arcuate surfaces.

8. A conveyer comprising in combination, a track having an unbridged space, containers adapted to be moved over the track, trunnions on each container projecting laterally outwardly of the track, means for pushing the containers toward said space, and means for moving the containers across said space and therebeyond in one continuous movement, said means including means for supporting the containers one at a time by their trunnions whereby the container contents may be dumped in crossing said space.

9. A conveyer comprising in combination, a track having an unbridged space, containers adapted to be moved over the track, trunnions on each container projecting laterally outwardly of the track, means for pushing the containers forwardly toward said space a distance substantially equal to the width of a container, means adapted to be projected upwardly behind the trunnions of the container nearest said space to move it along, and means for supporting the container by its trunnions while crossing said space whereby the container contents may be dumped into said space.

10. A conveyer comprising in combination,

a track having its continuity interrupted by an unbridged space, containers adapted to be moved along the track, means reciprocable alongside said space, means for establishing pivotal connection between the containers and said reciprocable means when the containers approach said space whereby the containers may tilt about the connection to dump the container contents into said space, means for pushing the containers forwardly toward said space a distance substantially equal to the width of a container and means actuated by the pusher means to start one complete reciprocation of said reciprocable means.

11. A conveyer comprising in combination, a track having an unbridged space, means reciprocable alongside said space in a path of travel longer than the distance across said space, containers adapted to be moved over the track, trunnions on the containers at one side of the center line thereof, means at the sides of said space for supporting the containers by their trunnions, means carried by the reciprocable means adapted to be projected behind the trunnions for moving them along, and means for reciprocating said reciprocable means.

12. In a furnace conveyer, the combination of a track having an unbridged space, containers adapted to be moved over the track, trunnions on the containers projecting laterally of the track, reciprocable means for supporting the containers by their trunnions while being moved across said space, and means engageable with the trunnions for moving the containers across said space.

13. A conveyer comprising, in combination, a work container, a container-supporting track interrupted by an unbridged space, means for passing the container over said space in a manner to dump the container contents into the space, said means comprising travelling means for engaging the container on pivotal connections at the side of the container.

14. A conveyer comprising, in combination, a track having its continuity interrupted by an unbridged space, means for pushing work-containers toward said space while supported on the track section leading toward said space, and separate means synchronized with said pushing means for moving the containers across said space in a manner to permit the containers to dump their contents.

15. In combination, a track having an unbridged space, pans movable on said track, trunnions projecting from the pans laterally of the track, means for moving the pans toward said space, and separate means at the sides of said space for moving the pans thereacross while hanging from their trunnions.

16. In combination, a track having an unbridged space, pans movable on said track, trunnions projecting from the pans laterally of the track, means for moving the pans to-

ward said space, and separate means at the sides of said space for moving the pans thereacross while hanging from their trunnions and delivering them in horizontal position onto the track therebeyond.
